UNITED STATES PATENT OFFICE

BARTON S. GORDON, OF TIFFIN, OHIO

WELL PIPE

Application filed July 27, 1932. Serial No. 625,082.

This invention relates to well construction, and aims to provide a well casing of a construction which will absolutely exclude surface water or water passing through earth formation that renders the water impure or objectionable for drinking purposes.

An important object of the invention is to provide sealing means at both the upper and lower ends of the well casing sealing the space 10 between the well casing and wall of the well.

A still further object of the invention is the provision of a casing section having an outwardly flared flange to engage the wall of the well and seal the well against water entering 15 the well from upper levels.

With the foregoing and other objects in view, which will appear as the description proceeds, the invention resides in the combination and arrangement of parts and in the 20 details of construction hereinafter described and claimed, it being understood that changes in the precise embodiment of the invention herein disclosed, may be made within the scope of what is claimed, without departing 25 from the spirit of the invention.

Referring to the drawing:

Figure 1 is a view illustrating a well casing constructed in accordance with the invention, as positioned in a well.

Figure 2 is a longitudinal sectional view through the casing.

Figure 3 is an elevational view of a modified form of well casing sealing device.

Referring to the drawing in detail, the well casing embodies a plurality of pipe sections 5, which are connected by the collars 6, the number of pipe sections being governed by the depth of the well.

Disposed near the upper end of the well casing are spaced packing rings 8, while packing rings 9 are arranged near the lower end thereof, guarding the ends of the space between the well and well casing, against foreign matter entering the space.

To further insure protection against surface water entering the well, the wall of the well near the upper end thereof is enlarged providing a recess or space for cement indicated by the reference character 10, which ce-

ment is packed firmly in position between the well casing and wall of the well.

The lower end of the pipe section at the base of the casing, supports the shoe 11 which has a flared lower end 12 that fits against the 55 wall of the well in which the casing is positioned.

An annular groove is formed exteriorly of the shoe 11, and is so disposed that it supports the copper sealing ring 13 in an inclined position, the free edge of the sealing ring contacting with the wall of the well, at a point in line with the lower edge of the shoe 11.

In the form of the invention as shown by 65 Figure 3 of the drawing, the lower pipe section of the well casing, indicated at 14, is supplied with a flared metallic flange 15, the same being secured to the well casing in any suitable and well known manner.

This flange 15 is so located on the well casing, that it will lie in a position adjacent to the clay or hard pan level, sealing the lower end of the well casing against water passing to the bottom of the well, through this earth 75 formation. This flange 15 provides a seat for the sealing material 16, which is poured into the space between the well and well casing, after the well casing and sealing ring have been positioned, and an enlargement in 80 the wall of the well has been made for the reception of the sealing material.

From the foregoing it will be seen that due to the construction shown and described, all surface water as well as the water passing 85 through mineral earth formations, will be excluded from the fresh water at the bottom of the well.

Having thus described the invention, I claim:

1. A sealing device for sealing the space between a well casing and the wall of the well in which the casing is positioned, comprising a shoe secured to the lower end of the casing, the lower end of the shoe being flared outwardly contacting with the wall of the well, said shoe having an annular groove formed therein, a sealing ring fitted in the groove and flared outwardly from the shoe, to contact with the wall of the well, sealing 95 100

the casing against water passing between the casing and wall of the well.

2. A sealing device for sealing the space between a well casing and the wall of the well, in which the casing is positioned comprising a shoe secured to the lower end of the casing, the lower end of the shoe being flared outwardly contacting with the wall of the well, an outwardly and upwardly flared member mounted on the shoe at a point above the lower end of the shoe, contacting with the wall of the well, and said outwardly flared end of the shoe, sealing the casing against water passing downwardly or upwardly between the shoe and wall of the well.

In testimony that I claim the foregoing as my own, I have hereto affixed my signature.

BARTON S. GORDON.
